CUTTING MACHINE

John Frederick Smith, Quincy, Mass., assignor to
Compo Shoe Machinery Corporation, New York,
N. Y., a corporation of Delaware

Application June 7, 1934, Serial No. 729,403

8 Claims. (Cl. 12—17)

This invention relates to slashing machines which are useful chiefly in shoe manufacturing operations.

A particular object of the present invention is to provide a machine for making one of the cuts for severing the complementary insole-outsole combinations shown in U. S. Patents Nos. 1,838,708 and 1,902,725, issued to F. Sbicca. In accordance with the showings in those patents, insoles and outsoles are cut from a single piece of stock in such a manner as to form an insole having a perforate forepart and an outsole having its forepart landed to mate with the insole. One method of forming these parts involves making a series of cuts in the stock, and the machine of the present invention is primarily adapted to make a beveled cut or slash which extends across the stock approximately at the ball line and which constitutes one of the cuts used to separate the insole from the outsole.

While the present invention accordingly is primarily useful in the above manner, certain benefits thereof may be obtained generally in other beveling and slashing operations. It is therefore contemplated that it may be used in any such operation to which its nature adapts it.

Further objects of the invention are to provide a machine of this kind which is rugged and efficient in its operation and with which the operator can readily perform the required operations.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a plan view of a machine embodying features of the present invention;

Fig. 2 is a longitudinal vertical sectional view taken along line 2—2 of Fig. 1;

Fig. 3 is a transverse vertical sectional view taken substantially along line 3—3 of Fig. 2;

Fig. 4 is a transverse vertical sectional view taken along line 4—4 of Fig. 2 and looking in the direction of the arrows; and

Fig. 5 is a fragmentary plan view showing the relationship of certain parts of the machine.

Referring more particularly to the drawings,

there is shown a base 10 in the form of a generally rectangular casting provided with an upper bed plate or table 11. Spaced upright journals 12 and 13 extend from this plate and have rotatably mounted therein a cam drive shaft 14 which is adapted to be power driven in the manner hereinafter described so as to operate a knife and a work clamping mechanism. A pair of cams 15 and 16 are eccentrically mounted on shaft 14 between journals 12 and 13. These cams are keyed to shaft 14 as by means of one or more pins such as 17. If only one pin is used, the abutting surfaces of cams 15 and 16 may be provided with suitable interlocking contours (not shown) to insure their rotation in unison. These cams operate the hereinafter described work clamping means.

Disposed between cams 15 and 16, and preferably integrally formed with one thereof, is an eccentric 18, about which is strapped a knife operating pitman 19. At its forward end this pitman is pivotally attached at 20 to a knife holder 21 (Fig. 2) which has a knife 22 disposed thereto. The tail portion of this knife is bifurcated as shown and is held against holder 21 by means of a holding plate 23 and screws 24 which latter pass between the forks of the knife tail. The knife holder 21 is slidably mounted on an inclined guideway 25 (Fig. 2) located on the upper portion of a work clamp or presser foot 26 which is adapted to hold the sole while the knife is operating. Holder 21 is confined in its guideway by retaining plates 27 which overlap the lateral edges thereof.

The presser foot 26 comprises the forward portion of a lever 28 which is pivotally mounted on the base at 29. A pair of spring housings 30 and 31 respectively underlie cams 15 and 16 and are mounted on lever 28. Presser springs 32 and 33 are respectively confined within these housings 40 at a predetermined pressure by slideable spring bolts 34 and 35, the upper heads of which are respectively adapted to be maintained in rubbing contact with cams 15 and 16 by means of a tension spring 36 which extends between a portion of journal 12 and clamping lever 28, giving the latter a normal bias upwardly. Clamping lever 28 is provided with an adjustable stop screw 37 which is adapted to limit downward movement thereof through contact with the surface 50 of bed plate 11. The forward under surface of presser foot 26 is provided with a work contacting plate 38 which may be ribbed, toothed or otherwise suitably roughened to afford a firm grip against work confined therebeneath.

In the preferred use of the machine this work takes the form of a complementary insole-outsole blank indicated at 39. Prior to its introduction to the present machine this blank is 5 suitably rounded out to approximately its final contour, and has a thickness corresponding to the combined thickness of the ultimately formed insole and outsole portions.

Positioning gages are provided for locating 10 such blank with respect to the knife. These include a toe abutting gage 40 which is attached to a slidable rack 41 for movement therewith by means of pin connections 42 which extend through a suitable slot 43 in the bed plate 11. A 15 pinion 44 is in engagement with rack 41 and is mounted on a shaft 45, which in turn is rotatably and slidably journaled in a bearing 46 forming part of the base 10 (Fig. 3). At its outer end shaft 45 has a manually operable adjusting knob 20 47 keyed thereto. This knob has its inner face toothed or serrated as at 48 and these teeth are adapted to lock against similar teeth on a fixed disk 49 attached to base 10. A spring 50 gives shaft 45 and knob 47 a normal bias toward disk 25 49, which bias may be overcome by pulling knob 47 out sufficiently to disengage the teeth at 48, at which time the shaft 45 may be rotated so as to operate rack 41 and toe gage 40 which is carried therewith. Knob 47 is suitably calibrated 30 as at 51 in order properly to locate toe gage 40 for any desired sole size.

In addition to toe gage 40 there are provided side gages 52 and 53 which respectively are adapted to cooperate with left and right soles. 35 These gages are mounted on a common transverse sliding bar 54 which is suitably pinned at 55 to a transverse rack 56. This rack is operable by pinion 57 which is keyed to a longitudinally extending shaft 58 having its forward end extending through the front wall of base 10 and provided with a manually operable knob 59. As 40 in the case of knob 47, this side gage control knob 59 is preferably calibrated with respect to a fixed mark on the base so that gages 52 and 45 53 may be slidably positioned to accommodate different sole sizes and may readily be correlated with the toe gage. As is clearly shown in Fig. 1, gages 52 and 53 are used alternatively, and when, as in that figure, a left sole is being positioned, 50 a three-point control of the sole is afforded through contact of the latter with the toe gage 40 and with two points along the side gage 52. The rack 56 controlling the side gages is adapted to be locked in any desired position by means 55 of a locking bar 60, best shown in Figs. 1 and 4, which is pivoted to a block 61 screwed to the under side of bed plate 11. Bar 60 is provided with a lateral projecting finger 62 which is adapted to be slidably positioned between adjacent 60 teeth on rack 56 and there to be held by means of a spring pressed plunger 63 (Fig. 4) abutting against the under side of bar 60. When it is desired to adjust the side gages, this locking bar is depressed by hand.

65 The described gage means effectively control the position of the knife cut laterally and longitudinally of the sole, and also control the angular location of such cut with reference to the long axis of the sole.

70 A one-revolution driving clutch is provided for operating the above described knife and clamping means. This driving mechanism includes a pulley 64 which is freely rotatable on an extension 14' of the cam shaft 14, and is confined 75 against inward movement therewith by means

of a collar 14" forming a part of such shaft. A clutch sleeve 65 is slidably keyed on shaft 14 between collar 14" and the adjacent face of journal 12 and is given a normal bias toward pulley 64 by means of spring pressed fingers 66 which are pocketed in journal casting 12. This clutch sleeve is provided with one or more recesses 67 into which corresponding pins 68, which are carried by the pulley 64, are adapted to fit in driving relation during such time as the slidable 10 clutch sleeve 65 is held in interfitting engagement therewith by means of plungers 66. Clutch sleeve 65 is adapted to be disengaged from driving pins 68 by means of a vertically disposed spring 15 pressed plunger 69 which normally presses 15 against the surface of a cam track 70 running about the periphery of sleeve 65. This track has an offset cam portion 71 which, as it slides past plunger 69, forces sleeve 65 axially along shaft 14 and out of engagement with the driving pins. 20 A depression 72 is located in the track 70 opposite cam 71 and affords entry to plunger 69, which latter holds the clutch sleeve 65 stationary in non-driving position once it enters such depression. A rod 73 is adapted to be operated by 25 any suitable foot treadle mechanism (not shown) and is attached to plunger 69 in order to depress the latter when desired. As shown in the drawings, the various operating parts associated with this driving clutch are in the driving relation 30 which obtains about midway of the operating stroke of the knife, plunger 69 being in sliding contact with the track 70 but out of engagement with cam 71 so that the sleeve 65 is in driving relation with pin 68 and thus transmits motion 35 to the shaft 14 from pulley 64, which is constantly rotated by a suitable driving belt.

As shown in Fig. 1, a counting device 74 is operatively attached at one end of shaft 14 so as to register each rotation thereof. Since the shaft 40 only rotates once to each sole treating operation, this arrangement accurately records the amount of work done on the machine.

In operation, a complementary insole-outsole blank which has been rounded out to determined 45 size is provided. The knobs 47 and 59 are adjusted by means of their respective calibrations to correspond to the selected sole size, the right or left gages 52 and 53 being alternately used as the nature of the particular sole to be operated 50 requires. With the gages properly positioned, the sole blank is located thereagainst in three point contact, as explained above, and the foot treadle rod 73 is depressed by the operator. This removes plunger 69 from depression 72, and the 55 retraction of plunger 69 is continued sufficiently to clear it from track 70 so that plungers 66 are free to press clutch sleeve 65 toward rotating pulley 64. Pins 68 enter recess 67 and impart driving motion to sleeve 65. When this motion 60 has proceeded sufficiently to advance cam 71 beyond the vicinity of plunger 69, such plunger may be released by the operator into sliding contact with the cam track, and upon one complete revolution of the clutch sleeve, plunger 69 will, 65 through engagement with cam 71 and entry into depression 72, effect disengagement and stoppage of the clutch sleeve. During rotation of shaft 14 the cams 15 and 16 which are carried therewith press against the spring bolts 34 and 35 and this 70 pressure is transmitted through springs 32 and 33 to the clamping lever 28, thus serving to bring presser plate 38 into tight gripping relation with the top of the work stock. When this gripping relation has been established, eccentric 18 is then 75

operative to drive knife 22 downwardly into the stock, thus effecting the required bevelled slash, which slash is accurately positioned on the work stock. The depth of the stroke can be controlled 5 through adjustment of the position of knife 22 with respect to its holder 21, this adjustment being readily effected by means of screws 24.

It will be seen that there has been provided a machine which is well suited to perform its intended functions. Since certain changes may be made in the above construction and different embodiments of the invention could be made without departing from the scope thereof, it is intended that all matter contained in the above description 10 or shown in the accompanying drawings shall be interpreted as illustrative and not in a limiting sense.

It is also to be understood that the following claims are intended to cover all of the generic and 15 specific features of the invention herein described, and all statements of the scope of the invention which, as a matter of language, might be said to fall therebetween.

Having described my invention, what I claim as 20 new and desire to secure by Letters Patent, is:

1. A machine for bevel slashing rounded sole blanks comprising a base providing a support for the blanks, a knife slidably mounted over said base for reciprocation into the blank, and gage 25 means for fixing the position of a given blank with respect to said knife, said means comprising selectively usable right and left side gages each adapted respectively to contact two points on the same side of a right or left blank, and a toe gage, 30 said side gages being mounted on a common sliding bar, and means for adjusting said bar laterally selectively to accommodate right or left blanks of varied sizes.

2. A machine for bevel slashing rounded sole 35 blanks comprising a base providing a support for the blanks, a knife slidably mounted over said base for reciprocation into the blank, and gage means for fixing the position of a given blank with respect to said knife, said means comprising selectively usable right and left side gages each adapted respectively to contact two points on the same side of a right or left blank, and a toe gage, 40 said side gages being mounted on a common sliding bar, and means for adjusting said bar laterally and said toe gage longitudinally selectively to accommodate right or left blanks of varied sizes.

3. A machine of the class described comprising a base providing a support for work stock, a work 45 clamp mounted over said base and having an inclined guideway, a knife slidably mounted in said guideway in position to enter said stock, a drive shaft, means operated by said shaft for increasing pressure between said clamp and work 50 stock positioned therebeneath, and connections be-

tween said shaft and knife for operating the latter.

4. A machine of the class described, comprising a base providing a support for work stock, a work clamp having one end pivoted to said base and its other end overhanging said stock, a knife mounted over said base in position to enter said stock, a compression spring seat on said clamp, a drive shaft, a cam fixed to said shaft in position to bear on said spring to transmit cushioned 10 pressure from said shaft to said clamp.

5. A machine of the class described, comprising a base providing a support for work stock, a work clamp having one end pivoted to said base and its other end overhanging said stock, a knife 15 slidably mounted on the overhanging end of said clamp in position to enter said stock, means for pressing said clamp toward said support, and means for driving said knife.

6. A machine of the class described, comprising a base providing a support for work stock, a work clamp having one end pivoted to said base and its other end overhanging said stock, a knife 20 slidably mounted on the overhanging end of said clamp in position to enter said stock, a drive shaft having a plurality of eccentric cams, spring cushioned connections between one of said cams and said clamp, and a pitman pivotally connecting another of said cams with said knife.

7. A machine for bevel slashing rounded sole 25 blanks comprising a base providing a support for a blank, a work clamp having one end pivoted to said base and its other end overhanging said blank, a knife slidably mounted on the overhanging end of said clamp in position to enter said stock, a drive shaft, connections driven by said shaft for pressing said clamp against and for driving said knife into said blank, a constantly 30 rotating driving pulley, a driving connection between said pulley and shaft, and means for automatically 35 disengaging said driving connection at the completion of one operating cycle of said knife and clamp.

8. A machine for bevel slashing rounded sole 40 blanks comprising a base providing a support for said blank, a work clamp having one end pivoted to said base and its other end overhanging said blank, a knife slidably mounted on the overhanging end of said clamp in position to enter 45 said blank, a drive shaft having a plurality of eccentric cams, spring cushioned connections between one of said cams and said clamp, a pitman pivotally connecting another of said cams with said knife, a constantly 50 rotating drive pulley, a driving connection between said pulley and shaft, and means for automatically 55 disengaging said driving connection at the end of one shaft rotation.

JOHN FREDERICK SMITH. 60
